UNITED STATES PATENT OFFICE.

CLAUDE A. HOOTON, OF SHERMAN, TEXAS, ASSIGNOR TO HARDWICKE-ETTER COMPANY, OF SHERMAN, TEXAS.

GIN ATTACHMENT.

Application filed July 11, 1921. Serial No. 483,854.

To all whom it may concern:

Be it known that I, CLAUDE A. HOOTON, a citizen of the United States, residing at Sherman, Grayson County, Texas, have invented a certain new and useful Improvement in Gin Attachments, of which the following is a full, clear, and exact description, such as will enable others skilled in the art to which it appertains to make and 10 use the same.

My invention relates to cotton gins. More particularly it is an attachment for cotton gins for the purpose of moving and regulating the feeding of cotton to the gin 15 and the ejection of refuse, hulls and chaff.

In the operation of the usual types of cotton gins, especially where the cotton is bolly, or contains many hulls or burrs, it is necessary to maintain attendants at the 20 gins whose duty it is to see to the cleaning of the gin of this waste at regular intervals. To do this the gin breast in front of the gin saws must be swung out sufficiently for the hulls and burrs to drop out 25 and then closed again. When the gin breast is opened the feeding of cotton to the gin must be checked until the gin is again closed. The attendant usually does this by hand. An obstruction is placed at the 30 mouth of the chute which feeds the cotton to the gin and the gin breast is then swung open to drop out the waste. When the gin is again closed, the feeding chute is opened and the ginning again proceeds.

The object of my invention is to provide 35 a mechanism, operated in connection with the gin itself, which will, at regular intervals, close the feeder, open the gin breast and discharge the hulls and waste and again close the gin and open the feeder.

A further purpose is to do away with the necessity of some of the attendants at the gins by performing the process of discharging hulls, etc., from the gin automatically, without the necessity of manual operation.

Further objects and advantages will be clear from the description which follows in which a preferred embodiment of my invention is disclosed. The invention lies particularly in the combination and relation of parts, and various obvious changes may be made therein without departing from the spirit of my invention.

Referring to the drawings wherein like

numerals of reference are applied to like parts throughout the several views: Fig. 1 is a perspective view of a gin stand with my invention applied thereto. Fig. 2 is a perspective view of the operating mechanism of my device. Fig. 3 is broken view showing the device in side elevation, and Fig. 4 is another perspective view thereof.

In the drawing, the numeral 1 designates the cleaner, having a feeding chute 2 thereon to conduct the cotton to the gin 3. At the front or breast of the gin 3 is a door 4 conforming in shape to the gin breast. It is hence of somewhat irregular shape and is hinged at each side of the gin stand adjacent the upper end of the door at 5. The cotton fed from the chute 2 to the gin 3 is acted upon within the gin to separate the lint from the seeds and bolls. The seeds and small objects may drop from the gin 75 through outlets specially constructed but the hulls and waste gather within the breast of the gin and interfere with the proper action of the gin. It is then necessary to open the door 4, swinging it out to the 80 dotted line position of Fig. 3 to allow the hulls to drop out. While this is done the cotton from the feeder must be shut off by closing the opening 6 leading therefrom.

These operations are performed by means 85 of my invention. The opening 6 of the feeding chute is provided with a door or valve 7 connected at one of its side edges to a rod 8 pivoted to swing in forked brackets 9, one at each side of the mouth of the 90 chute.

This door is held normally in open position by means of a weighted lever 10 fixed to the rod 8 and extending rearwardly with a slight upward inclination as shown in 95 Fig. 1. The lever is maintained in this position by means of a connecting rod 11, pivotally attached to the said lever at a point 12 spaced a short distance from the lower end of the lever. The other end of 100 the connecting rod 11 is supported on the outer end of an operating lever to which said connecting rod is detachably secured.

To raise the breast door 4 of the gin, a laterally extending bracket 14 on the breast 105 door is provided with an opening therein to which is detachably secured a connecting rod 15. This rod extends backwardly and upwardly and is connected at its other end to an operating lever 16. The rod is 110

inserted in an opening in the said operating lever and is secured against removal by a cotter pin or some other detachable means.

The operating levers 13 and 16 are actuated by the mechanism shown best in Fig. 2. This mechanism is housed in a box 17. The housing 17 has a central upright shaft 18 therein upon which is mounted a gear wheel. Said wheel is adapted to be operated by a worm gear 20, formed on a transverse shaft 21 journaled in the box 17. The outer end of this shaft has thereon a pulley which may be operatively connected by means of a belt 23 to a smaller pulley 24 on a shaft of the cleaner 1.

The two operating levers 13 and 16 are pivoted at one side of the housing on a pin 25. This pin is on that side of the box 17 away from the gin stand 3. A slot 26 in the lower half of the housing provides a guide for the lower lever 16. The upper lever moves in a slot 27 in the lower face of the upper half of the housing which is removable so as to form a cover for the mechanism.

The gear wheel 19 is mounted so as to set in a horizontal position midway between the two operating levers. On the upper face of the wheel and closely adjacent the outer edge are a plurality of evenly spaced cam blocks 28. The outer face of each of these cam blocks is rounded to contact with the upper lever 13 as the gear wheel rotates.

On the lower face of the wheel are a like number of rollers 29 shown in dotted lines in Fig. 2. These rollers are slightly behind the cams 28, as the wheel rotates, and are positioned to bear against the lever 16 and throw it over slightly after the upper lever is operated and, because of its shorter surface of contact with the lever, will also allow it to swing back sooner than can the upper operating lever.

The housing is supported by any convenient means such as a bracket 30 as may be most desirable, at a point near the gin stand. The rotation of the pulley 22 by means of the belt, or any other convenient means, will cause the rotation of the wheel 19 in a clockwise direction as viewed in Fig. 2. As the wheel rotates the cam 28 will come in contact with the upper lever 13 first. This will act to shove it forward into the position shown in Fig. 4. This motion of the lever will act through the connecting rod 11 to throw the weighted lever 10 into raised position and close the door or valve 7 as shown in Fig. 4.

The roller 29 on the lower face of the gear wheel will then strike the lower operating lever 16 and force it forward to the position shown in Fig. 4 and thus throw the rod 15 and the breast door 4 forwardly so as to allow the waste to be discharged.

The continued rotation of the wheel 19 will bring the roller 29 out of contact with the lever 16 and the weight of the door 4 will cause it to drop back and throw the lever 16 into its rearward position. The cam 28 will then pass the lever 13 allowing the weight 10 to drop and open the door 7 and throw the lever 13 back.

The continued rotation of the gear wheel 19 will shortly bring another set of cam and roller into engagement with the levers 13 and 16 and repeat this operation. The proper spacing of the cams and the timing of the gear will serve to close the valve 7 and shut off the feed of the cotton and to then open the door to the gin breast and discharge the hulls, close this door and then open valve 7 and feed the cotton again to the gin and to repeat this operation regularly at the proper intervals of time.

As will be noted, this device is simple and positive in its action and is not liable to easily get out of order. It may quickly be attached or detached from its operative position. Thus, where the cotton is clean, and the device unnecessary, the belt may be removed, the valve 7 may be lifted from the brackets 9, and the connecting rod 11 detached from the operating lever 13. The connecting rod 15 may also be quickly detached and removed. The gin may then be run as usual. If a poor quality of bolly cotton is again to be ginned, the device may be as quickly installed and operated. It may easily be set up for operation on any ordinary type of gin stand with little expense.

Having thus described my invention, the further advantages and objects of which will be clear to one skilled in the art, what I claim as new and desire to protect by Letters Patent is:

1. In a device of the character described, a gin, a door therefor, a feeder chute, a valve therefor, operating levers connected to said door and valve, a rotating gear and separate means on said gear to actuate each of said levers to close said valve and open said door, said door being adapted to close and said valve to open by action of gravity when said levers are released by said means.

2. In a device of the character described, a gin, a door thereon, a feeder chute, a valve therefor, said door being normally closed and said valve normally open, two levers pivoted on a common shaft, a gear between said levers, cams on opposite sides of said gear contacting with said levers to move them, operative connections between one of said levers and said door and similar connections between the other lever and said valve whereby said valve may be closed and said door opened at predetermined intervals.

3. In a device of the character described,

a gin door, normally closed, a feeder valve, normally open, a housing, upper and lower operating levers pivoted on said housing, a gear wheel between said levers, means on 5 said gear wheel to move said levers, connections between said levers and said door and said valve to close said valve and open said door, said door and valve being adapted to automatically return to normal position when said levers are released.

4. In a device of the character described, a pivoted member normally open, a second member normally closed, a separate lever connected with each of said members, 15 means to operate said levers to first close said open member, to then open said second member, said operating means being adapted to release said levers to close said second member and then open said first member 20 in the manner described.

5. In a device of the character described, a feeder valve normally open, a door nor-

mally closed, a supporting housing, a lever thereon operatively connected with said valve, a second lever connected with said door, a rotating gear, a cam thereon adapted to actuate the valve lever and a separate cam to thereafter operate said door lever in the manner described.

6. In a device of the character described, 30 an open valve, a closed door, an operating lever connected to said valve, a second lever connected with said door, a rotatable gear wheel adjacent said levers, cams on said wheel arranged to throw said valve lever to close said valve, throw said door lever to open said door and to then release said door lever and afterwards release said valve lever to open said valve in the manner described.

In testimony whereof, I hereunto affix my signature, this the 1st day of July, A. D. 1921.

CLAUDE A. HOOTON.
